UNITED STATES PATENT OFFICE.

CHARLES WILLIAM PRESSLEY, OF HOLLYWOOD, CALIFORNIA.

DESIGN FOR A GOLDEN HARP PIANO.

Application filed December 27, 1927. Serial No. 24,670. Term of patent 14 years.

To all whom it may concern:

Be it known that I, CHARLES W. PRESSLEY, a citizen of the United States, residing at Hollywood, in the county of Los Angeles and State of California, have invented a new, original, and ornamental Design for a Golden Harp Piano, of which the following is a specification, reference being had to the accompanying drawings, forming part thereof.

Fig. 1 is a perspective view looking toward the front of a golden harp piano, showing my new design.

Fig. 2 is a perspective view looking toward the rear of a golden harp piano.

I claim:

The ornamental design for a golden harp piano substantially as shown.

CHARLES WILLIAM PRESSLEY.
